US00D955855S

(12) **United States Design Patent** (10) **Patent No.:** **US D955,855 S**
(45) **Date of Patent:** **** Jun. 28, 2022**

(54) **HANDLE**

- (71) Applicant: **WHIRLPOOL CORPORATION**,
Benton Harbor, MI (US)
- (72) Inventors: **Daniel Chow**, St. Joseph, MI (US);
Daniel V. Clements, St. Joseph, MI
(US); **Christopher A. Gregory**, St.
Joseph, MI (US); **Patrick J. Schiavone**,
Benton Harbor, MI (US); **Mark W.**
Schulz, Benton Harbor, MI (US)
- (73) Assignee: **Whirlpool Corporation**, Benton
Harbor, MI (US)
- (**) Term: **15 Years**
- (21) Appl. No.: **29/753,932**
- (22) Filed: **Oct. 5, 2020**

Related U.S. Application Data

- (63) Continuation of application No. 29/588,793, filed on
Dec. 22, 2016, now Pat. No. Des. 901,277.
- (51) **LOC (13) Cl.** **08-06**

(57) **CLAIM**

The ornamental design for a handle, as shown and described.

DESCRIPTION

FIG. 1 is a perspective view of a handle according to the design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a front elevation view thereof; and,

FIG. 7 is a back elevation view thereof.

The portions of the article shown in even broken line form no part of the claimed design. Dash-dot-dash broken lines represent the bounds of the claimed design and form no part thereof.

1 Claim, 3 Drawing Sheets

US D955,855 S
